CLOTH TENTERING MECHANISM FOR
LOOMS

Arthur E. Benson, South Attleboro, Mass.

Application August 17, 1938, Serial No. 225,365

11 Claims. (Cl. 139—293)

This invention relates to an improved cloth tentering mechanism for looms comprising an improved loom temple construction adapted for operation in a novel manner to prevent injury to the cloth through the breakage of selvage threads, as well as to prevent the formation of indentations or fine openings in the fabric through the use of toothed clamping jaws or rolls provided with radial pins.

One object of the invention is the provision of a mechanism of this character adapted to grip the edges of the cloth and effect a lateral stretching of the fabric in coordinated relation with the movement of the lay beam, to bring the width of the fabric into substantial correspondence with the length of the reed during those periods when the filling threads are beaten up into close relation through movement of the lay beam.

Another object of the invention is the provision of a mechanism adapted to release its grip on the fabric immediately upon the completion of the forward movement of the lay to permit free movement of the fabric under the influence of a take-up mechanism, whether the take-up mechanism is operated over a long or short period of the movement of the lay, and generally regardless of the time of its occurrence during the cycle of movement of the lay.

A further object of the invention is to eliminate the formation of openings or perforations in the woven fabric through the use of rotating cloth engaging members having pins engaging the cloth, and provide gripping means of a character adapted to operate without injury to fine silk, cotton, rayon or other fabrics of a fine texture.

A further object of the invention is the provision of novel and improved gripping means for engaging the lateral edges of the fabric and novel means for operating the same to effect lateral movement of the gripping means outwardly of the fabric at suitable intervals while leaving the fabric free at all other times to move without interference from the temples during the constant or intermittent operation of appropriate take-up mechanism.

A further object of the invention is the provision of means actuated by movement of the lay for gripping and tentering the fabric during a brief interval in the "beat up" of a filler thread beginning immediately prior to the completion of the full forward movement of the lay and terminating when the lay has receded a substantially equal distance from its full forward position, leaving the fabric free during the remainder of

the cycle of movement of the lay for actuation by the take-up means without interference from the gripping mechanism.

A further object of the invention relates to the provision of a novel form of gripping means for engaging and gripping opposite edges of the cloth.

Other objects and advantages of the invention relate to various improved details of construction and numerous novel parts and arrangements of parts making up the structure, as well as improved methods of operating the same such as will be more fully set forth in the detailed description to follow.

Referring to the drawings—

Fig. 1 is a top plan view of a portion of a loom, certain of the parts being broken away, and showing portions of the breast beam and lay beam with associated mechanisms operable for tentering the cloth.

Fig. 2 is a vertical sectional view, taken substantially along the line 2—2 of Fig. 1, and showing the relative arrangement of certain of the operating parts, and showing the gripping jaws in open position.

Fig. 3 is a vertical sectional view through a portion of the temple mechanism and breast beam, taken substantially along the line 3—3 of Fig. 1.

Fig. 4 is a vertical sectional view through the gripping jaws, taken substantially along the line 4—4 of Fig. 1, showing the jaws in closed position, and illustrating the cloth engaging elements.

Fig. 5 is a vertical sectional view through a portion of the lay beam, taken substantially along the line 5—5 of Fig. 1.

Fig. 6 is a front elevational view of a portion of the lay beam, showing the bumper and its manner of attachment to the face of the lay beam, and,

Fig. 7 is a front elevational view of a portion of the breast beam, showing the relation of the gripping jaws and the means for imparting movement thereto laterally of the cloth through operation of the slide mounted on the breast beam.

Heretofore, various forms and arrangements of cloth templing and tentering mechanisms have been employed in connection with the formation of woven fabrics, employing various forms and arrangements of loom temples adapted for operation in various ways, including the provision of non-laterally-displaceable gripping jaws, and the use of laterally displaceable constantly engaging means such as rollers provided

with radial teeth or pins adapted for constant engagement with the fabric. In the first case, the use of non-laterally-displaceable gripping jaws fails to stretch the fabric laterally in such a manner as to give it a width corresponding substantially with the effective length of the reed and thus fails to prevent or minimize the abrasion or breakage of weft threads in selvage portions of the fabric by movement of the reed. In the use of each of these constructions the provision of pins or teeth engaging fine fabrics tends to injure the selvage edges by forming perforations or depressions in the cloth that detracts from its appearance, particularly in the case of fine fabrics, and may result in a breakage or fraying of the threads.

In the embodiment of the invention illustrated herein the loom frame 1, breast beam 2, lay 3, reed 4 and means for moving the lay 3 may be of any usual or desired character adapted for the purpose for which they are employed. A suitable guide bar or roll 4' may be supported in any desired manner from the frame 1, over which the woven fabric may pass to a suitably driven sand roll 5 and thence to the usual cloth roll 6 which may be operated by any suitable form of take-up mechanism (not shown) as is usual in devices of this character.

Mounted upon the breast beam 2 are suitable grooved supporting plates 7 and 8 for each temple slide 9, the supporting plates 7 and 8 being secured to the breast beam by bolts 10 and 11, respectively. The supporting plate 7 may be fixedly secured to the breast beam while the supporting plate 8 may be capable of limited adjustment longitudinally thereof through the slot 12 receiving the bolt 11.

Each temple slide 9 is mounted for sliding movement longitudinally of the breast beam in the grooved ends of opposite supporting plates 7 and 8, the extent of its sliding movement being determined by the adjusted position of its supporting plate 8. An actuating arm 14 is secured to or formed integral with each slide 9 and may project outwardly beyond the front edge of the breast beam and be provided with an end slot 15. A spring 16 may be provided to connect the arm 14 or other portions of the slide with a portion of the supporting plate 8 for returning the slide 9 to its normal retracted position after actuation.

A bracket 17 is adjustably secured to the front face of the breast beam by means of a screw or bolt 18 passed through a slotted opening in the bracket. Each bracket 17 is located at a point adjacent to one of the actuating arms 14 carried by a slide for pivotally supporting an elbow lever 19, which is provided with a lug 20 adapted to fit within the end 15 of the actuating arm for moving the slide 9 longitudinally of the breast beam.

Each temple slide 9 is provided with a longitudinally extending slot 21 providing means for adjustably mounting a temple holding bracket or base 22 thereon by means of a clamping bolt 23. Each temple bracket 22 supports adjustably a temple holder 24 having a base 25 and a cap portion 26, said base and cap having projecting flanges 27 engageable by one or more clamping screws 28 or the like to hold the base and cap together when removed from the temple holding base. A clamping bolt 29 or similar fastening means is passed through a slot 30 formed in the flanges 27 for adjustably securing each temple holder 24 to its bracket 22. Each temple holder 24 provides a support for a sliding temple rod or

shank 32, the stem 33 of which extends within the holder and is provided with a spring 34 disposed between a shouldered portion of the shank and the reduced end 24' of the holder, whereby the spring 34 normally acts to hold the temple rod or shank 32 and its attached temple in its position nearest the lay. The temple rod or shank 32 extending from the holder 24 towards the lay is provided with upper and lower temple jaws 35 and 36, one of which is movable towards and from the other in order to clamp and hold the fabric at intervals and release it at other times in the operation of the mechanism.

In that form of the invention, shown herein, the lower jaw 36 is formed integral with or fixedly secured to the shank 32, and the upper jaw 35 is pivotally mounted on the shank 32 by means of a pivot bolt 38 for pivotal movement towards or from the jaw 36. The upper jaw member 35 is provided with a rearwardly and downwardly extending arm 39 to which is pivotally secured a trigger arm 40, as at 41, and the lower end portion of the arm 39 may be provided with a locking screw 42 extending through an arcuate slot 43 formed in the trigger arm 40 for adjustably securing the trigger arm 40 to the arm 39 in any one of a plurality of angularly adjusted positions. The weight of the combined arm 39 and trigger arm 40 located upon one side of the pivot bolt 38 is such as to more than counterbalance the weight of the jaw 35 on the opposite side of the pivot bolt 38, and thus maintain the jaws normally in open position at all times except when pressure is applied to the trigger arm 40.

A laterally slidable detent 45 may be secured to the fixed or lower jaw 36 by means of a screw or like holding means 46 in position to be turned inwardly over the movable jaw 35, as shown in Fig. 1 of the drawings, to limit the extent of separation of the jaws and at the same time limit the extent of angular movement by the trigger arm 40 when released by its operating instrumentality.

Suitably mounted upon the lay beam, as upon the under face thereof, is a bracket 48 in which is slidably supported a trigger engaging member 49 having a portion normally projecting forwardly from the lay beam, the member 49 being provided with a slot 50 for receiving a tension spring 51, one end of which may be secured to the bracket 48 by a screw or like fastening means 52, the opposite end being secured to a portion of the member 49, as indicated at 52', whereby the member 49 is resiliently supported in the bracket 48. The member 49 is suitably positioned for engaging the trigger arm 40 as the lay beam approaches its forward position and presses the member 49 against the trigger arm 40 resiliently, through action of the spring 51, to rotate the upper jaw 35 about its pivot 38 and close the jaws upon the edge of the fabric therebetween.

A bumper plate 53 is suitably mounted on the lay beam 3, being preferably provided with a slotted opening 54 to receive the fastening screw 55 or the like in such a manner as to be capable of adjustment longitudinally of the lay beam. The bumper plate 53 may be provided with a bumper face 56 of any suitable or desired character located in appropriate position to engage the lever arm 57 of the elbow lever 19 for moving the temple slide 9 longitudinally of the breast beam and outwardly laterally of the fabric. The arrangement of these operating elements is such that the trigger arm 40 is first engaged by the resilient slide member 49 to move the upper jaw 35 into fabric gripping relation with the lower 75.

jaw 36, and immediately thereafter the lever arm 57 of the elbow lever 19 is engaged by the bumper face 56 of the bumper plate 53 to move the temple slide 9 outwardly laterally of the fabric.

5 The lower jaw 36 of the movable jaws 35 and 36 may be provided with a recess 60 formed in the upper face thereof and surrounded by an upwardly extending edge or rim 61, for receiving a pad of leather, cork or the like 62, preferably of slightly less height than the rim 61, which pad may be held in position by rivets 63 or by being cemented or otherwise secured to the face of the jaw 36. A pad 64 of cloth, felt or the like may be secured to the operating face of the jaw 35, as by means of rivets 65, or by being cemented, glued or otherwise fixedly secured to the face of the jaw 35. The edges of the fabric material being woven are consequently gripped directly by the pads 62 and 64 to prevent injury to the fabric material, 20 and upon release of the gripping actuating means, the slightly raised edges 61 of the jaw 36 will support the fabric substantially out of contact with the face of the pad 62 as the fabric is drawn thereover by action of the take-up 25 means.

It will be understood from the showing contained in Fig. 1 of the drawings that it is proposed to employ duplicate temple structures at each edge of the fabric being woven, and, aside 30 from the fact that one is a right and the other a left temple, they may be of substantially the same construction throughout and each provided with similar operating mechanisms correspondingly positioned for effecting similar operations of the 35 temple mechanisms in correspondence with each other and at corresponding periods in the movement of the lay beam.

As is well known by those skilled in the art, the lay on the forward movement carries the last shot of filling with it toward the "fell" of the cloth, and, at the moment of beating up drives such filling into place closely adjacent the previous shot, which may be in a different warp shed. Such action of the lay when the fabric is not held 40 in a laterally extended position corresponding substantially with the effective length of the reed tends to cause a longitudinally extending gather or width reduction in the cloth, which tends to cause abrasion of or injury to certain of the warp threads through engagement by the reeds. To avoid these defects, the present invention contemplates the provision of means for temporarily and positively gripping opposite lateral edges of the fabric and moving the same outwardly laterally of the fabric as each filling is beaten up into place by movement of the lay, so that the reed wires will not abrade the warp threads as the filling is driven into place. The 45 substantially immediate release of the gripping jaws after the lay starts to return permits operation of the cloth take-up means either substantially continuously, or at any point in the movement of the lay beam, except that in which the filling is actually being driven into place, without 50 any interference through operation of the gripping means engaging opposite lateral edges of the fabric.

From the construction as shown and described 55 it will be apparent to those skilled in the art that as the lay moves to the "beat-up" and immediately prior to the full forward movement thereof, the resiliently mounted members 49 will engage the trigger arms 40 and cause the upper jaws 35 to move about their pivots 38 to grip resiliently 60 the edge of the fabric between the jaws 35 and

36. Immediately upon the closure of the gripping jaws and in timed subsequent relation therewith the bumper faces 56 will engage the lever arms 57 of the elbow levers 19 to actuate the temple slides 9 for moving both temples outwardly 5 simultaneously in a direction laterally of the fabric to bring the width of the fabric into substantial correspondence with the effective length of the reed as the filler thread is driven into place upon the full forward movement of the lay. As 10 the lay returns after each "beat-up" the bumper faces 56 first release the lever arms 57 of the elbow levers 19 and immediately thereafter the resiliently mounted members 49 release the trigger arms 40 to permit the jaws 35 and 36 to open 15 through the counterbalancing action of the arms 39 and trigger arms 40.

While the gripping jaws and temple moving means are shown herein as actuated directly from the lay, it will be understood by those skilled in 20 the art that these mechanisms may be actuated by other means which may in turn be actuated by or in timed relation with the movement of the lay. The actuation of the gripping jaws to grip the cloth preferably takes place shortly before the 25 lay completes its full forward movement and the gripping jaws may be released at a corresponding period in the return movement of the lay. Accordingly, the outward lateral movement of opposed gripping jaws from each other occurs in 30 the interval between the actuation and release of the gripping jaws, and the entire duration of the cloth gripping action is only a small part of the 35 cycle of movement of the lay. Consequently, the cloth is free to move without interference by the gripping jaws during substantially the entire cycle of movement of the lay.

The terms "lay" and "lay beam" as employed in the specification and claims are to be understood as comprising or including all parts and 40 portions of the oscillatory lay beam structure adapted to participate in its movement towards and from the breast beam during the usual forward and return movements of the lay beam in the weaving operation.

What I claim is:

1. In a tentering mechanism for a loom having a lay movable for beating up the filler threads in the warp, clamping means and means for moving said clamping means to positively grip opposite edges of the woven fabric prior to the completion of the full forward movement of the lay, and means independently of said last named means actuated by the lay for moving said clamping means outwardly from each other simultaneously 50 immediately after being moved into and while in clamping engagement with the fabric.

2. In a tentering mechanism for cloth looms, a lay, oppositely positioned cloth gripping means, means actuated by the lay for moving said cloth gripping means into and retaining them in cloth gripping position, and means separate from said first named lay actuated means actuated by the lay for moving said cloth gripping means outwardly from each other while in gripping engagement with the cloth.

3. In a tentering mechanism for cloth looms, a lay, displaceably mounted cloth gripping means movable to grip opposite edges of the cloth and displaceable bodily outwardly from each other laterally of the cloth, and separately effective means operated by the lay prior to the completion of the full forward movement of the lay for actuating said gripping means to grip the cloth and displace said gripping means outwardly from 70 75

each other successively, said means being operated by the lay during the return movement of the lay to release said actuating means in the reverse order of their occurrence.

5. In a loom, temples having jaws between which the opposite side edges of the woven fabric passes, a lay, jaw actuating means for causing said jaws to close upon the fabric, and means separate from said jaw actuating means operated by the lay prior to the completion of the full forward movement of the lay for displacing said temples outwardly from each other transversely of the fabric while said jaws are in gripping engagement with opposite sides of the fabric.
10. 6. In a tentering mechanism for cloth looms, a breast beam, oppositely positioned cloth gripping means carried by said beam and mounted for sliding movement longitudinally thereof, a lay, means for moving said cloth gripping means into gripping engagement with opposite edges of the cloth, and means actuated in timed relation with the movement of the lay for sliding said cloth gripping means outwardly from each other while in gripping engagement with opposite edges of the cloth.
15. 7. In a tentering mechanism for cloth looms, oppositely positioned cloth gripping means engageable with opposite side edges of the cloth, a lay, means for moving said cloth gripping means into clamping engagement with opposite side edges of the cloth and out of clamping engagement therewith during one complete cycle of movement of the lay, and means effective during the period when the cloth gripping means are in clamping engagement with the cloth for displacing said cloth gripping means outwardly bodily from each other laterally of the cloth and returning the same to their initial positions prior to the movement of said gripping means out of clamping engagement with the cloth.
20. 8. In a tentering mechanism for cloth looms, oppositely positioned temples each having a pair of jaws relatively movable to clampingly engage or release a selvage edge of the cloth, a lay beam, means actuated by the lay beam prior to the completion of the full forward movement of the lay beam for moving the jaws of oppositely positioned temples into clamping engagement with selvage edges of the cloth without lateral displacement of the temples, and means actuated by the lay beam prior to the completion of the full forward movement of the lay beam in subsequent timed relation with said first named means for laterally displacing said temples relative to each other after the jaws have been moved into clamping engagement with selvage edges of the cloth.
25. 9. In a tentering mechanism for cloth looms, a lay, oppositely positioned movable jaws for grip-

ping positively opposite edges of the cloth, means for moving said jaws into cloth gripping position, means for displacing said oppositely positioned jaws outwardly from each other along straight line paths at right angles to the direction of movement of the cloth while in gripping engagement with the cloth, and separate means operated by the lay during the forward movement thereof for actuating said jaw gripping and displacing means successively and in the order named.

10. 10. In a tentering mechanism for looms, a lay, fabric gripping means located upon opposite sides of the formed fabric and normally out of gripping engagement with the fabric, means actuated by the lay during the forward movement of the lay for moving said gripping means into gripping engagement with opposite side edges of the fabric, means separate from said last named means for moving said gripping means outwardly from each other while in gripping engagement with the fabric, and means operable by the lay during the rearward movement of the lay and upon the release of said last named moving means for moving said gripping means towards each other and out of gripping engagement with the fabric.

15. 11. In a loom, temples having gripping jaws between which the fabric passes, a lay, gripping jaw actuating means operated by the lay for causing said jaws to close upon the fabric as the lay approaches its front position, means operated by the lay effective during the return movement of the lay for moving said gripping jaws out of gripping engagement with the fabric, and means independent of said first named gripping jaw actuating means operable by the lay during the forward movement of the lay for moving said temples outwardly from each other during the period in which the fabric is engaged by the gripping jaws.

20. 12. The combination with a loom structure comprising a breast beam, and a lay beam movable towards and from said breast beam, of means carried by said breast beam for slidably supporting fabric gripping members whereby said fabric gripping members may be moved towards and from each other, fabric gripping members mounted on said supporting means and each provided with a fixed jaw and a movable jaw, means for actuating said movable jaws to grip the fabric at opposite selvage edges thereof, and means for sliding said fabric gripping members outwardly from each other while said jaws are in gripping engagement with the fabric, whereby the fabric may be gripped at opposite side edges thereof and lateral tension applied thereto while the same is engaged by said gripping jaws.

ARTHUR E. BENSON.
